UNITED STATES PATENT OFFICE

ALVA L. SKINNER, OF BRIDGEPORT, ILLINOIS, ASSIGNOR TO THE OHIO OIL COMPANY,
OF FINDLAY, OHIO, A CORPORATION OF OHIO

PUMPING POWER

Original application filed February 4, 1929, Serial No. 337,514. Divided and this application filed July 15, 1930. Serial No. 468,162.

This invention is a division from my application for a pumping power, filed February 4, 1929, Serial Number 337,514.

This invention relates to pumping power devices, and particularly to such devices which are used for pumping a number of oil wells from a single point, or station, at the same time. It is customary for such machines to be in constant operation, day and night, and it is, therefore, necessary for them to be constructed with a view to great durability. It is also necessary for them to be thoroughly lubricated, at all times, and of simple construction, so as to prevent mishaps necessitating the shutting down of the mechanism with a resultant halt in the pumping. As it is customary to pump a large number of wells with one apparatus, it will be readily understood that a stop, for repairs, for a comparatively short time, would result in a material reduction in output.

One object of the invention is to provide a construction possessing durability and simplicity, and which will prevent foreign matter from entering the working parts.

Another object is to provide a construction which will be compact, readily accessible with respect to its various parts, and that will occupy a minimum amount of space.

Another object is to provide a novel and simple means for connecting the pump rods to the power ring of the device.

Other objects and advantages will be apparent from the following description when taken in connection with the accompanying drawings.

In the drawings:

Figure 1 is a vertical transverse sectional view of a pumping power unit made in accordance with the present invention.

Figure 2 is a top plan view of the invention.

Figure 3 is an enlarged vertical sectional detail view through one of the pumping rod connections.

Figure 4 is an enlarged horizontal sectional view on the line 4-4 of Figure 3.

Figure 5 is an enlarged horizontal sectional view on the line 5-5 of Figure 3.

Referring particularly to the accompanying drawings, 10 represents a housing in which is mounted a horizontally disposed worm-shaft 11, and a vertical shaft 12. Secured to the lower end of the shaft 12, within the housing 10, is a worm-wheel 13, which meshes with and is driven by the worm-shaft 11. Keyed on the shaft 12, above the housing 10, and arranged in superimposed spaced relation to each other, are the eccentric members 14 and 15, each having a hub portion 16, a channeled rim portion 17, and a series of connecting spokes 18. Upon reference to Figure 1, it will be noted that the major portions of the members 14 and 15 extend in diametrically opposite directions, from the shaft 12. The upper face of the bottom wall of the rim portion of the member 14 is formed with the steps 20, 21 and 22, while the outer or marginal wall constitutes an upwardly and outwardly extending flange 17^a, having an inwardly directed circumscribing rib 17^b, at its upper edge. Disposed within the channel of the member 14 is a power ring 19, having the shoulders 19^c and 23, on its lower face, which rest, respectively, on the steps 20 and 22. It will be noted that these shoulders result in an annular groove 24, which overlies the step 21, whereby to provide an oil channel to receive an accumulation of oil to be supplied to the adjacent parts. It will also be noted that the marginal wall of the ring 19, adjacent the flange 17^a, is inclined to conform therewith and spaced slightly therefrom. This is for a purpose which will be later set forth. The periphery of the power ring is formed with an extension bead or rib 25, which extends over the upper face of the flange 17^a, to prevent entrance of foreign matter at this point.

To maintain the power ring properly seated within the channel of the rim 17, for rotary movement therein, a retaining ring 26, T-shaped in cross section, has its vertical rib 26^c disposed between the inner face of the power ring 19 and the inner wall of the channeled rim 17, with its head overlying the power ring 19 and the inner wall of the channeled rim 17. This retaining ring 26 is secured to

the said inner wall by means of the screws 27, and between the meeting faces, a paper, or other suitable gasket 27^a is employed. On the upper face of this inner wall there is formed a vertical bead 28, while a similar bead 29 is formed on the upper face of the power ring 19, and between these beads the said head of the retaining ring 26 is disposed. The beads 28 and 29 are to prevent oil from flowing on the upper surfaces of the adjacent parts on which they are formed.

Formed on the upper face of the power ring 19, are the upwardly extending studs 31, each of which has the transverse recess 32, in one side of its upper end, which is intersected by a vertical opening 33, formed through the upper end of the stud, and centrally thereof. A bolt 34 is disposed in the opening 33, with its head snugly seated within the recess against rotation therein. A sleeve 35 is fitted on the stud and has the inner portion of its upper end beveled, as at 36, and rising above the upper end of the stud.

Disposed on the upper end of the bolt, and arranged within the upper end of the sleeve 34, is a beveled disk 38, a nut 39 being engaged on the bolt to properly clamp the parts together, but permitting free rotation of the sleeve on said stud. Extending laterally from the sleeve 34 is a clamp 40, in which is secured one end of one of the pumping rods 41.

Formed in the face of the inner wall of the channel of the rim 17 is a circumscribing oil groove 42, and in the adjacent face of the stem or web of the retaining ring 26 there is formed a similar groove 42', such grooves being at the same level, and cooperating to form a circumscribing channel. In the inner face of the power ring 19, at the same level as the grooves 42 and 42', is a groove 43, said groove having communication with the groove 42' by means of a series of transverse oil passages 44, formed through the vertical web 26' of the retaining ring 26. Extending from the groove 42 is an oil passage 45, which registers with the lower end of the vertical oil passage 46, formed in the inner portion of the head of the retaining ring 26. Properly secured in the upper end of the passage 46 is one end of the oil pipe or conduit 47. Secured on the upper end of the shaft 12 is a sleeve 48, and formed on the upper end of said sleeve is a cup 49. Connected to the bottom of said cup 49 is the other end of the before-mentioned pipe 47. It will be noted that the pipe 47 leads to a point of the eccentric 14 near the shaft 12, through the retaining ring 26.

At the upper end of the shaft 12, and properly fitted within the bearings 50, is a cap member 51, for supporting said shaft. This cap is formed with an upwardly extending peripheral flange 52, through which are dis-

posed, and secured, the inner ends of the radially extending brace rods, which are adapted to be anchored at a suitable point.

Secured in the bottom wall of the member 51, is a suitable lubricant container 57, preferably of the automatic gravity feed type. Passing through the step 22, of member 14, at a point opposite the passage 45, is a vertical oil passage 58, and secured in the lower end of said passage is an oil pipe 59.

The member 15 is of similar construction to that described in connection with the member 14, and has the power ring 60 disposed in the channel, such ring being held in the channel by means of the retaining ring 61, and being provided with upwardly extending studs 31', constructed in a manner similar to the studs 31, of the power ring 19. The power ring 60, and the inner wall of the channel, are formed, respectively, with the oil grooves 63 and 64, between which communication is established by means of the oil passages 60', formed through the vertical web of the retaining ring 61. The groove 64 has the vertical oil passage 65 which registers with the passages 66, in the head of the retaining ring 61. The lower end of the before-mentioned oil pipe 59 is secured within the upper end of this oil passage 66. The lower face of the power ring 60 is formed with the annular oil groove 67, similar to the groove 24, of the ring 19. Leading downwardly through the bottom of the channel of the member 15, from the ledge 68, is an oil passage 69, within which is secured one end of the oil pipe 70, said pipe having its other end secured in the outer end of the oil passage 71, formed in the hub member 16, of the member 15, and which passage extends to a point directly above a bearing 72, located in the upper portion of the housing 10, and which surrounds the shaft 12.

The operation of the device may be briefly described as follows: Power being applied to the worm shaft 11, to rotate the same, the vertical shaft 12 will also be rotated, carrying around the channeled members 14 and 15. As the members 14 and 15 rotate about their axes, the power rings will be given eccentric rotary movements, whereby to cause the reciprocation of the pumping rods 41, and the operation of the pumps at the wells.

By removing the nut 39, from the bolt, the disk 38 may be lifted from said bolt, whereupon the operator may slip the sleeve 34 from the stud 31, or slip a sleeve thereon. Thus the number of pumping rods may be increased or diminished, in accordance with the number of wells to be operated.

What is claimed is:

1. A pumping power unit including a shaft, an eccentric channeled member mounted on the shaft, a power ring seated within the channel of the member, and a retaining ring disposed between the power ring and

the eccentric member and having a head secured to the eccentric member and overlying the power ring.

2. A pumping power unit including a shaft, an eccentric member mounted on the shaft and having a circular channel, a power ring seated within the channel and spaced from one wall of said channel, and a retaining ring T-shaped in cross section having its web disposed in the said space and its head overlying the eccentric member and the power ring, and means removably securing a portion of the head of the retaining ring to the eccentric member.
- 10 3. A power ring for a pumping power unit including a body, upwardly extending studs on the body, pumping rods each having a terminal means movably engaged on a stud, and means for retaining said terminal means on the stud, said retaining means including means engaged with said terminal means, and means on the stud engaged with the terminal engaging means, for holding the latter in position.
- 20 4. A power ring for a pumping power unit including a body, a plurality of upwardly extending studs on the body, each of said studs having a vertical opening in its upper end opening through a side of the stud, a pumping rod having a terminal sleeve engaged on the stud, a bolt held in said opening, and a disk held on said bolt in retaining relation to said sleeve.
- 28 5. A power ring for a pumping power unit, including a body, a plurality of upwardly extending studs on the body, each of said studs having an opening in its upper end extending through the upper end of the stud and the side thereof adjacent said end, a pumping rod having a terminal movably engaged on said stud, a fastening means held within the stud opening by the said terminal, and means held engaged with said rod terminal by said fastening means.
- 35 45 In testimony whereof, I affix my signature.
ALVA L. SKINNER.
